UNITED STATES PATENT OFFICE

2,430,063

LATERAL GUIDING MEANS FOR HEAVY
DOOR POSTS

William J. Laufersweiler and Royal E. Thompson,
Columbus, Ohio, assignors to The Kinnear
Manufacturing Company, Columbus, Ohio, a
corporation of Ohio

Application February 15, 1943, Serial No. 475,912

2 Claims. (Cl. 189—46)

1

The primary object of the invention is to provide improved means adjacent the bottom of the door for guiding a pilaster or mullion over an obstruction or elevated portion of the floor, whereby the necessity for the use of a track in the floor is eliminated; in a preferred form this means takes the form of a cable which is readily removable from the door opening after the pilasters and mullions have all been moved to the sides of the opening.

Other objects will more fully hereinafter appear.

In the accompanying drawings:

Figure 1 is an elevation of a door embodying the principles of the present invention; this view is taken from within the hangar.

Figure 2 is a horizontal section of a modified form wherein the mullion for the central section of the door is adapted to be guided by a cable instead of by a deck track in its movement to the side of the door opening.

Figure 3 is an enlarged elevational view showing details of the cable guiding means for guiding the mullion in its movement to the side of the door opening.

Figure 4 is a section on the line 4—4 of Figure 3 looking in the direction of the arrows.

Figure 5 is a section taken on the line 5—5 of Fig. 3 looking in the direction of the arrows.

Referring to the drawings in detail, and first particularly to Figure 1, the opening of the hangar is adapted to be closed by three flexible rolling steel curtains 4 which are made up of inter-engaging slats 5 and are adapted to be rolled upwardly about a drum contained within a drum housing to thereby open the door. The bottom bar of the door, designated as 3, is provided with a rubber seal 2 adapted to engage the deck 1 of the ship. A movable pilaster 8 is provided at the intersection of adjoining curtains and serves to guide the curtains in their vertical movement and to support them against movement inwardly or outwardly. At the sides of the door opening a stationary pilaster 9 is provided. Intermediate the pilasters there is provided a movable post known as a mullion and designated by reference numeral 10. Mullion 10 serves to guide the door in its vertical movement and to reinforce it against inward pressure of water or wind, the door or curtain being disposed outwardly of mullions 10, as will appear from Figure 2. Mullions 10 and movable pilasters 8 are adapted to be locked into position by locking rods 11 which are adapted to engage sockets 34 in the deck, and other sockets (not shown) in the superstructure,

2

directly thereabove and to be locked or unlocked by a hand wheel 12. In this way, the mullions and pilasters can be unlocked in order to move them out of the door opening. As will be apparent, the curtains 4 will be raised before the locking means 11 is unlocked, the pilasters and mullions being subsequently moved out of the way.

In order to reinforce the lower portion of the door 4 against water, a water bracing is provided. This bracing is made up of horizontal members 15 to which are pivotally dependent vertical braces 14 which extend down to a point adjacent the bottom of the door. Members 15 are pivoted at 13 with respect to mullions 10 and the opposite end is adapted to be received behind a locking member 20 on pilasters 8 and 9. Lines 16 are provided for raising and lowering the water bracing, as will be apparent from Figure 1.

20 Mullions 10 and movable pilasters 8 are supported from an I-beam track 19 by means of a trolley, or carrier, designated generally as 17. Trolleys 17 pivotally support the heavy mullion or pilaster as by means of a pivot shaft 20 or in 25 any other suitable manner. The trolley wheels 25 are adapted to ride upon the upper surface of the lower web 21. In order to motivate the trolley 17 along the track 19 an endless hand chain 22 is provided which extends downwardly to a point where it can be readily operated by hand from the deck. Chain 22 encircles a wheel 23 which connects with any suitable type propelling mechanism for moving the heavy pilasters and mullions by operating the chain.

30 The load is pivoted on the trolley 17 so as to allow it to swing parallel to the plane of the overhead track 19 without lifting an end of the carriage upwardly off the track 19.

Track 19 is made up of two portions, each of 40 which extends from a point adjacent the side of the door opening to the center of the door opening, the track being outwardly inclined at a slight angle relative to the curtains 4, as will be apparent from the drawings. This angle is such

45 that the trolleys employed in the usual construction will all engage a common track. However, in the construction of Figure 2 it is not possible to use a common track for all trolleys, it being necessary to use a single separately disposed track for the central mullion 10.

The ends of the curtain 4 are received and guided by the intermediate movable pilasters 8 (see Figure 1). These ends of the curtain are received within guide slots on either side of 55 pilaster 8.

The mullions 10 are provided on their forward faces with wood strips 41 (Figure 4) which are adapted to engage the curtain with a minimum of friction.

For guiding the lower end of the pilasters 8 or the mullions 10 in their movement to the side of the door opening, a number of different methods may be employed. A deck track 42 is shown in Figure 2. The deck track 42 may be mounted either above or below the deck. Casters are provided at the bottoms of the mullions 10 and pilasters 8 for engagement with deck track 42. The deck track 42 will be inclined at an angle relative to the door (see Figure 2) and parallel to the trolley track or tracks 19 which will be located exactly thereabove. In Figures 2 and 3 to 5 there is illustrated an alternative form of construction wherein the hangar has an upwardly inclined runway 44 in its center, and has a slanting deck surface 45 at either side of the runway 44, the sections 45 and 44, merging at the joint line 46. Surface 45 slants downwardly from the edge of the runway 44 towards the sides of the hangar where it merges with a horizontal surface 47. The central mullion 10 is thus unable to be guided by a deck track because its lower end is elevated above the lower ends of the first mullion 10 and the first pilaster 8. Accordingly, a flexible stayline 48 is provided for guiding the central mullion 10, this line 48 being stretched tautly parallel to deck track 42 between a pin 49 located adjacent the center of the door opening and a vertical assembly 50 located at the side of the door opening. This stayline 48 has ears 51 at its outward end which are adapted to be slidably received over a forwardly extending pin 52 slidably mounted in the upper end of vertical pin 49. The other end of stayline 48 is provided with a member 54 extending through vertical assembly 50. An internally threaded end wheel 55 is provided on the outward end of this member 54, whereby stayline 48 may be tautened. Mullion 10 is provided at its lower end with ears 56 adapted to slidably engage stayline 48 and guide mullion 10 in its movement. As indicated in Figures 2 and 5, a socket 34 is provided below the inclined surface 44 for the reception of locking pins 33. A roller 57 mounted on support 58 (Fig. 5) is provided for rollingly engaging stayline 48. Thus, central mullion 10 is adapted to be moved back and forth along stayline 48. After it has been moved to this position at the side of the door opening adjacent vertical assembly 50, hand wheel 55 may be rotated so as to loosen stayline 48 whereupon its inward end may be removed from attachment with vertical pin 49, by pulling slidable pin 52 out of ears 51. The stayline 48 may then be removed to a position at the side of the hangar. Thereafter, when it is desired to move the mullion 10 into position, stayline 48 will be replaced and the mullion will be moved to the center of the door opening by the actuation of trolley 17 by means of hand chain 22.

For locking the pilasters and mullions at the side of the opening, sockets 59 (Figure 2) are provided in the deck and corresponding sockets (not shown) are provided in the superstructure. In this way, the mullions and pilasters may be locked by means of locking rods 11 at the sides of the door opening.

This application is a division of our application Ser. No. 291,944, filed August 25, 1939.

Having thus fully described our invention, what we claim as new and desire to secure by Letters Patent is:

1. In association with a door, a movable post member, means for guiding the lower end of said post member in its movement, comprising a stayline extending parallel to the path of movement of said movable member and positioned adjacent to the bottom of said movable member, means fixedly attached to the bottom of said movable member for guiding the bottom of said movable member in its movement, said last named means including spaced ears having portions encircling said stayline at spaced points along said stayline, a supporting member extending between said ears, and roller means mounted on said supporting member and rollingly engaging said stayline at a point between said encircling portions.

2. In association with a door, a movable post member, means for guiding the lower end of said post member in its movement, comprising a stayline extending parallel to the path of movement of said movable member, a bracket fixedly attached to the bottom of said movable member and having a pair of sleeves spaced from each other for encircling said stayline for guiding the bottom of said movable member in its movement, said bracket including spaced supports for said sleeves and a third support connecting said supports first named and extending longitudinally of said stayline, and a roller having a bearing in said third support for positioning said roller substantially midway between said sleeves and between said movable member and said stayline at a point between said sleeves for rollingly engaging said stayline said roller having its axis of rotation substantially perpendicular to said stayline for spacing the lower portion of said movable member relative to said stayline for preventing friction between said sleeves and said stayline.

WILLIAM J. LAUFERSWEILER.
